DESIGN FOR AN ENCLOSED HOUSING FOR ELECTRICAL APPARATUS

Raymond H. Olley, Syracuse, N. Y., assignor to
Creuse-Hinds Company, Syracuse, N. Y., a cor-
poration of New York

Application March 8, 1939, Serial No. 83,443

Term of patent 14 years

To all whom it may concern:

Be it known, that I, Raymond H. Olley, a citizen of the United States, residing at Syracuse, in the county of Onondaga and State of New York, have invented a new, original, and ornamental Design for an Enclosed Housing for Electrical Apparatus, of which the following is a specification, reference being had to the accompanying drawing forming part thereof.

In the drawing:

Figure 1 is a front elevational view in perspective of an enclosed housing for electrical apparatus showing my new design.

Figure 2 is a side elevational view.

Figure 3 is a top plan view.

I claim:

The ornamental design for an enclosed housing for electrical apparatus, as shown.

RAYMOND H. OLLEY.
